AUTOMOBILE RADIATOR GRILLE WITH
DETACHABLE SECTIONLee B. Green, Lakewood, Ohio, assignor to The
Globe Machine & Stamping Company, Cleve-
land, Ohio, a corporation of Ohio

Application December 31, 1934, Serial No. 759,883

22 Claims. (Cl. 293—54)

My invention relates to a metal grille for guarding an aperture, its general objects being that of providing a grille which will present the appearance of a unitary and artistically harmonious construction, and which will allow a section of the grille to be readily detached for affording access to what is behind that section without requiring the grille to have either a continuously exposed opening for that purpose.

10 In one of its immediate commercial aspects, my invention relates to grilles used on the so-called radiator shells on passenger automobiles for guarding the frontal air-admitting openings in these radiator shells, and for partially concealing the radiator cores behind the said shells; for which purpose such grilles are commonly constructed of parallel blades fastened to cross-members. In this aspect, my invention aims to provide a two-part grille which will present a substantially unitary appearance while also overcoming the following objections to the entirely unitary automobile radiator grilles now in common use:

15 (1) Since such a frontal grille on an automobile usually extends across an extension of the axis of the shaft of the manually operable starter mechanism, a grille for this purpose has usually been provided with a correspondingly positioned opening through which a hand crank can be inserted for operating the said mechanism. In practice, the inserted end portion of the hand crank usually has a diameter many times that of the spacing between consecutive blades of the grille, so that the needed crank-admitting opening would extend across many blades of the grille. Consequently, these blades are constructed of aligned sections and the adjacent ends of the blade sections are usually connected by a crank-hole plate which necessarily is of much greater spread than the said crank-admitting opening.

20 This plate in itself interrupts the general appearance of the blade; and its aperture affords an undesirably large opening for admitting stones or the like, unless this opening is normally closed by a detachable cover, in which case the cover itself may easily be lost.

25 (2) Such a frontal grille on an automobile is generally spaced forwardly from the radiator core, so that the suction fan behind this core will draw air through a much greater portion of the said core than that directly in front of the fan, and this spacing is considerably increased when the grille has a V-sectioned or a forwardly bowed front. Consequently, both dust, mud and snow gradually collect on the so-called apron which

usually underhangs the space between the radiator core and the grille, thereby permitting such mud and the like to pile up on the said apron until it can readily be seen through the grille. When this has occurred, the usual smallness of the spacing between the consecutive blades of the grille prevents the inserting of a brush or the like for scraping the deposit off the apron, or even for adequately reaching these accumulations with a jet of water for washing them off.

30 (3) The customary disposition of such a grille—which in modern passenger automobiles is fastened to the rear or inward face of the radiator shell front and hence cannot be removed without first detaching the radiator shell from the chassis—also prevents any ready access to the radiator core from the front of the latter. Consequently, it is difficult even for a garage mechanic to clean the so-called “core cells” (or air passages through this core) adequately, and without such an occasional cleaning the water-cooling efficiency of the radiator is considerably reduced.

35 My present invention aims to overcome all of the just recited objections to the now customary automobile radiator grilles in the following general manner:

(A) By providing a generally integral grille from which a section can readily be detached, desirably manually or without requiring more than a mere screw-driver for detaching it, and thereafter manually replaced, while still preserving the continuity of the grille-blades or other pattern-forming elements of the grille so that the grille will simulate the desired unitary appearance.

(B) By constructing the detachable section in a blade grille main of blade portions which extend in continuation of non-detachable blade portions, so that the grille still adequately retains such a unitary appearance.

(C) By disposing the detachable section so that it will extend across an extension of the axis of the manually operable starter shaft, thereby permitting a hand crank to reach this shaft when the said section is detached.

(D) By making the detachable section sufficiently wider than the shaft-gripping end of the usual hand crank as to permit a user to insert both his fore-arm and a brush or the like through the opening left in the grille when this section is detached, thereby enabling any one to clean dirt or snow off the said apron speedily, or likewise enabling a garage attendant to reach a consider-

able portion of the radiator core behind the grille with the nozzle of a compressed air hose.

In addition, my invention aims to provide a grille construction for the above recited purposes, 5 in which the detachable section may be of any desired height and width in proportion to the total exposed width and height of the grille, and in which the detachable section will be firmly held against rattling.

10 Still further and also more detailed objects will appear from the following specification and from the accompanying drawings, in which

15 Fig. 1 is a front elevation of the lower mid-width portion of a V-front automobile radiator grille embodying my invention.

Fig. 2 is a similar elevation, taken after the detachable section has been removed.

20 Figs. 3 and 4 are rear elevations of the parts A and B respectively of Fig. 1.

25 Fig. 5 is a horizontal section taken along the line 5—5 of Fig. 1, with a portion of the latch engaging member broken away.

Fig. 6 is a vertical section taken along the line 6—6 of Fig. 1, but showing a taller detachable 30 section.

Fig. 7 is a rear perspective view of the detachable section alone, with its mid-height portion broken away.

Fig. 8 is a rear perspective view of the latch- 35 engaging member alone.

Figs. 9 and 10 are sections, allied respectively to upper and lower portions of Fig. 6, taken while the detachable section was being attached to the main and stationary part of the grille.

35 Fig. 11 is a section allied to Fig. 9, showing the interlocking of the latching spring with the central blade of a V-front grille when this is a wide blade.

Fig. 12 is a section allied to Fig. 6, showing an 40 alternative construction of numerous parts.

In the drawings, I am showing my invention as applied to a grille of the widely used type in which parallel and substantially upright blades of rearwardly open section are cross-connected by vertically spaced cross-members or so-called tie-bars, 45 and in which my invention permits all of the blades to present an apparently continuous appearance while still allowing a laterally central lower section of the grille to be easily detached.

50 To provide for the detachability of such a grille portion, I make all of the blades 1 with the exception of a central group of blades continuous throughout the length of the grille, and connect these single-piece blades 1 by cross-members which rigidly space them. As here shown, each such continuous blade has rearwardly projecting web tabs T extending through slots S in a rearwardly open channel-sectioned cross-bar C disposed above the opening in the grille which 55 is normally closed by the detachable section of the grille, these tabs being clinched against the rear face of the cross-bar as shown in Fig. 3. The lower end portion of each continuous grille blade 1 is fastened to a lower cross-bar, and to 60 make this cross-bar serve also as part of a socket for receiving the lower portions of the detachable grille section (which is shown separately in Fig. 7) I desirably construct this lower bar of two angle-sectioned strips.

65 In the drawings, this cross-bar has as its smaller portion an angle-sectioned metal strip comprising a riser web 2 (which may bear rearwardly against the blades to stiffen the assembly) and also has a rearwardly projecting web 2a; while the larger 70 angle-sectioned strip includes a taller riser web 3

which has its upper portion extending in front of and welded to the riser web 2 of the companion strip. This larger strip also includes a rearwardly projecting web 3a which is spaced downwardly from the aforesaid rearwardly projecting web 2a, and each single-piece blade is shown in Fig. 4 as anchored to the double-strip lower cross-bar by deforming the blade web portions 1a, which extend between the two webs 2a and 3a, after the manner more fully disclosed in my co-pending application #746,873, filed October 4, 1934 on a Grille-blade and cross-bar assembly.

10

To make the other blades of the grille simulate single piece blades also, I construct each of these other blades of two alined sections, with the upper blade section 4 of each such two-piece blade extending downwards slightly beyond the cross-bar C and fastened to the latter (as shown in Fig. 3) in the same manner as the continuous blades 1. Then I provide a detachable grille section which includes the companion sections 5 of the two-sectioned blades, together with means for rigidly spacing these companion sections similarly to the upper sections 4 of the two-sectioned blades, and which detachable grille sections also 15 includes part of the means for firmly latching the detachable section to the major rigid part of the grille.

20 For these purposes, Figs. 6 and 7 show the detachable blade sections 5 as anchored near their upper ends to a cross-bar 10 of rearwardly open channel-section, and near their lower ends to a similarly sectioned cross-bar 1. These two cross-bars 10 and 1 have parallel ends spaced by substantially the same distance as the adjacent 25 blade-webs of the two continuous blades (1b and 1c in Fig. 2) which define the sides of the opening normally spanned by the detachable section, so that the engagement of the cross-arm ends with the last named two continuous blades will 30 prevent a lateral shifting of the detachable grille section.

35 I also provide means on both of the cross-bars 10 and 1 to which the continuous blades are anchored, for normally preventing both a forward and a rearward movement of the detachable grille section. For this latter purpose, Fig. 6 shows the upper web 2a of the lower cross-bar as supporting and fastened (as by a weld W) to a horizontal web of an angle strip which also includes 40 a riser web 8a, the latter web being so spaced from the riser web 2 of the smaller strip section of the lower cross-bar that the said riser web 8a will engage a rearward portion of the lower cross-bar 1 of the detachable grille section 45 when the blade portions 5 of that grille section bear forwardly against the said riser web 2 of the lower cross-bar as in Fig. 6.

50 Thus constructed, the webs 2, 8 and 8a in Fig. 6 form a socket into which the lower end of the detachable grille portion can readily be inserted, particularly when the rearward riser web 8a of this socket slopes upwards slightly away from the forward web 2 to permit the lower end of the detachable grille section to be tilted from the 55 position shown in Fig. 10 to that of Fig. 6 during the attaching of the detachable grille section. The just recited sloping of the rearward riser web 8a also permits the detachable section to be rocked upon the bottom of the said socket when that section is being attached or detached, as in Fig. 10. Consequently, this socket effectively acts as a sill-forming portion of the stationary grille part. Moreover, when this socket is constructed of thin metal, as in Figs. 6 and 10, the resiliency 60

70

75

of the metal can also facilitate the said rocking while still causing the socket to fit snugly against the parts of the detachable grille section which it houses.

- 5 In addition, I make each blade-section 5 of my detachable grille part of a length approximating the vertical spacing between the web 8 (on which the lower ends of these blade sections normally seat) and the lower ends of the stationary companion blade sections 4. By doing this, I make the junctures J (Fig. 1) so inconspicuous as to require close observation to notice them, thereby making the completed grille appear as if all of its blades were of single-piece 15 construction.

To limit the rearward movement of the upper part of the detachable grille section and to insure an alinement of the adjacent ends of the two portions 4 and 5 of each two-piece blade, 20 I provide a stop fastened to the stationary part of the grille and adapted to be engaged by upper portions of the blade parts 5 of the detachable grille section when this grille section has been swung sufficiently rearward (after its lower 25 end was inserted in the previously described socket arrangement as shown in Fig. 10) to bring the sections 4 and 5 of each two-piece blade in alinement.

For this purpose I am here showing the cross-bar C as having its lower web C¹ overhanging and fastened to the approximately horizontal web 9 of an angle-sectioned latch-engaging member which also includes a stop web 9a depending from the forward edge of the said web 9 and adapted 35 to engage the rear edges of the blades 5 of the detachable grille section, as shown in Fig. 6.

To latch the detachable grille section to the stationary part of the grille when these two parts have thus been assembled, I also provide inter-engaging means on these two parts adjacent to the upper end of the detachable section, and desirably construct these means so as to facilitate their releasing. For this purpose, Figs. 6 and 7 show a spring 11 formed of flat metal, the forward portion of which spring overlies and is fastened to the upper web of the upper cross-bar 10 of the detachable spring section. This spring has its rear end portion 11a curled to an incomplete tube, the juncture of this curled spring portion with the more forward portion of the spring being disposed so that when the blade parts of the detachable grille section engage the stop web 9a, the rear edge of the web 9 of the stop member (of Fig. 8) will bear rearwardly 40 against the said curled spring portion 11a as shown in Fig. 6, and so that the uncurled part of the spring will press upwardly against the bottom of the web 9. Thus disposed, the curled spring portion draws the upper portion of the detachable section rearwardly to press it against the stop flange 9a, while the upward pressure of the uncurled spring portion cooperates with gravity to press the lower end of the detachable grille section against the bottom 8 of the heretofore described socket.

To simplify the attaching of the spring, I desirably notch its forward end portion 11b (as in Fig. 5) so that this will straddle the rearward portion of a blade directly in front of the spring, as in Figs. 5 and 7, thereby enabling a single rivet 12 to serve as the means for fastening the spring to the cross-bar 10. I also provide the stop web 9a of the said stop member with a notch 9b wider than the spring, so that the spring can pass this stop web. In addition, I desirably bow a rearward

portion 9c downwardly to enhance the latching effect without requiring the rear end of the spring to be disposed unduly high above the cross-bar 10 to which the spring is fastened.

With my spring latch thus constructed, so that the curled portion 11a will readily enter under the forward part of the web 9 of the stop member while the detachable grille section is being attached (as in Fig. 9), the depressed portion 9c of this stop member will flex the rear end of the spring downwards when the said grille section is being tilted farther rearward to its normal position, and the curled spring portion will snap behind the said depressed portion as soon as the detachable grille section reaches its halted position of Fig. 6.

When the detachable section is to be removed, the spring can readily be released by inserting the tip of a screw-driver 14 alongside the blade section 5 which is straddled by the spring, as shown 20 in dotted lines in Fig. 6, thereby permitting the said detachable section to be detached manually from the stationary main part of the grille, and no tools whatever are required for the replacing of the attached grille section.

Indeed, I have found in practice that I can obtain an adequately secure latching when the spring is of such moderate tension that the grasp of a garage mechanic suffices for pulling the upper 30 end of the detachable section out of its latched position to the position of Fig. 9, after which this section can more easily be grasped to lift its lower end out of the socket for the latter.

By making the cross-bars 7 and 10 of the detachable section of the grille of such length that they will fit slidably between the two grille blades 1b and 1c of the stationary part of the grille, I enable these cross-arms to prevent any lateral movement of the detachable section. By disposing the spring 11 so that it presses the detachable 40 section downwards against the web 8 which forms the bottom of my heretofore described socket formation on the stationary part of the grille, I also cause the detachable section to be rigidly supported even when the adjacent ends of the two-part grille blades do not quite abut against each other. Consequently, I guard against rattling without requiring the detachable grille section to include a frame and requiring the stationary grille portion to include a second frame closely 45 fitting the aforesaid frame, or requiring any other auxiliary rattle-preventing provisions. Consequently, the cost of my grille is only slightly greater than that of the usual grille, in which all blades are continuous throughout their length, and indeed no higher than the usual cost of such a grille when provided with a ring-shaped member bordering a crank-admitting aperture.

With the illustrated dimensions of my full-sized figures, the opening which is uncovered 60 when the detachable section is removed will obviously permit the insertion of a hand crank for reaching the corresponding shaft, which shaft usually is at a height not much above the lower end of such a grille. In addition, this opening 65 will also permit a hand to reach through it with an air nozzle for blowing deposits out of cells of the usual radiator core behind the grille, or for manipulating a brush to scrape dirt or snow off the apron which usually underhangs the space between the radiator core and the grille. Consequently, my here presented invention presents far greater advantages than the usual provision in an automobile radiator grille for inserting a hand crank.

However, while my full-sized drawings of Figs. 1 and 2 show the detachable section of a height which would be a minor fraction of the height of a radiator grille on an automobile, and also 5 show this section as of much less width than its height, it should be obvious that the height of this section can readily be varied; also, that its width can easily be varied by having it include sections of a larger proportion of the total number of 10 blades in the grille.

So also, while I have illustrated my invention as applied to a grille of the now popular V-front type, obviously could be used equally with grilles of flat, bowed or other frontal configurations by 15 merely shaping the several cross-bars to the corresponding frontal contours. It will likewise be obvious that such detachable sections could also be employed on grilles for other purposes—as for example on an air-outlet or air-inlet grille for 20 air-conditioning cabinets, when access to some part behind such a grille is desirable. Hence I do not wish to be limited as to the purposes for which my here presented grille is to be used.

Furthermore, while I have illustrated and described my new grille in an embodiment including numerous details of construction and arrangement which I have found easy to manufacture and advantageous in operation, I do not wish to be limited in these respects, since many changes 30 might be made without departing either from the spirit of my invention or from the appended claims.

For example, if the central blade of a grille is of a wider U-section than the usual quite narrow ones, the spring 11 may have its forward end portion 11c extending into the interior of this central blade and fitting against the inward faces of the two blade webs, instead of having this end of the spring forked and straddling the blade as 40 in Fig. 5.

Illustrative of other alternative details, Fig. 12 is a section allied to Fig. 6, showing the lower cross-bar 15 of the stationary part of the grille as having a widened U-back portion affording a 45 shoulder 15a, and showing the upper channel web 15c of this cross-bar having its rearward portion 15b bent upward to cooperate with the main portion of the said web and with the said shoulder to afford a socket for receiving the lower 50 ends of the blade-portions 5 of the detachable grille section.

Fig. 12 also shows the relatively higher cross-bar C of the stationary grille part as having its lower channel web C² fastened to a strip 16 of spring metal which has its forward end portions 16a bent downward to form a stop engaging the blade parts 5 of the detachable grille section. In addition, Fig. 12 shows the spring strip 16 as having its rear end portion 16b curved upward so 60 that the curled end portion 17a of a spring 17 (fastened to the upper cross-bar 10 of the detachable grille section) will snap behind it, thereby permitting the resiliency of the two spring strips 16 and 17 to cooperate to effect the latching. 65

I claim as my invention:

1. A substantially upright fabricated metal grille comprising a rigid main and stationary grille part having an aperture in its lower portion intermediate of its width and also having a sill-forming portion extending across the lower end of the said aperture, and a detachable grille section normally spanning the said aperture; the detachable grille section and the said sill-forming portion of the main grille part having 70

interengaging parts preventing both a forward and a rearward movement of the lower end of the detachable section with respect to the sill-forming portion, but permitting the detachable grille section to be rocked forwardly about the sill-forming portion; stop means fast on the main grille part for limiting the rearward movement of upper portion of the detachable grille section; and latching means interposed between the upper portion of the detachable section and the stationary grille part for normally holding the said upper portion in engagement with the stop means. 10

2. A grille as per claim 1, in which the main grille part includes a stiffening bar extending adjacent to the upper end of the said aperture, 15 to which stiffening bar the stop means are fastened.

3. A grille as per claim 1, in which the main grille part includes a generally horizontal bar adjacent to the upper end of the said aperture, 20 and in which the stop means comprise a stop member fastened to the said bar, the stop means including a web against which portions of the detachable grille section normally bear rearwardly.

4. A grille as per claim 1, in which the detachable grille section has side portions thereof fitting respectively against portions of the main grille part which form the sides of the said aperture so as to prevent a lateral shifting of the 25 detachable section. 30

5. A grille as per claim 1, in which the main grille part includes a stiffening member extending adjacent to the upper end of the said aperture, and in which the latching means comprise a spring fast with respect to the detachable grille 35 section and normally engaging a portion of the stiffening member.

6. A grille as per claim 1, in which the main grille part includes a stiffening member extending adjacent to the upper end of the said aperture, and in which the latching means comprise a spring fast with respect to the detachable grille section and normally engaging a portion of the stiffening member; the said spring presenting its forward portion below the stiffening member to 45 permit the insertion of a tool therebetween for disengaging the spring with the said portion of the stiffening member.

7. A substantially upright metal grille comprising a main and stationary grille part having an aperture in its lower portion intermediate of its width, and also having a sill-forming portion extending across the lower end of the said aperture, and a detachable grille section normally 50 spanning the said aperture, the detachable grille section and the said sill-forming portion of the main grille part having interengaging parts 55 formed for preventing both a forward and a rearward movement of the lower end of the detachable section with respect to the sill-forming portion, but permitting the detachable grille section to be rocked forwardly about the sill-forming portion; a stop member fast on the main grille part and presenting a frontal portion within the upper portion of the said aperture, against which 60 frontal portion the detachable grille section normally bears rearwardly; and latching means fast upon the upper portion of the said detachable section and normally engaging a rearward portion of the stop member to press the detachable 65 section against the said frontal portion.

8. A grille as per claim 7, in which the latching means are disposed for urging the detachable grille member both forwardly and downwardly.

9. A grille as per claim 7, in which the latch- 75

ing means comprise a spring having its forward portion fastened to the detachable grille section; the said spring having a more rearward portion normally snapped behind the stop member.

5 10. A grille as per claim 7, in which the said frontal portion of the stop member is of greater width than the spring and has a recess through which the spring can move during the attaching and detaching of the detachable member.

10 11. An upright grille comprising two horizontally spaced sets of spaced and substantially upright blades, a bottom cross-member extending across the space between the said two sets and connecting the said blades near the lower ends 15 of the blades; a more elevated second cross-member connecting the blades of both sets and extending effectively across the space between the two sets of blades intermediate the height of the blades; an intermediate set of spaced and substantially upright blades disposed between the aforesaid two sets of blades and fastened to the said second cross-member, the blades of the said intermediate set extending not materially downward beyond the second cross-member; a detachable grille section comprising upright blades of equal number and spacing as those of the intermediate set, and cross-bars respectively rigidly connecting upper and lower portions of the blades of the intermediate set; an upwardly open socket 20 fast with respect to the said bottom cross-member, in which socket the lower ends of the blades of the detachable grille section are seated, the last named blades normally presenting their upper ends adjacent to and in alignment with blades of the said third set; stop means fast with respect to the said second cross-member, against which stop means the detachable grille section normally bears rearwardly; and latching means normally pressing the upper portion of the detachable grille 25 section against the stop means.

12. An upright grille as per claim 11, in which the latching means also normally press the detachable grille section downwardly into seating relation to the said socket.

45 13. A grille as per claim 11, in which the said socket comprises an upwardly open U-sectioned member normally having its U-shanks respectively engaging forward and rearward portions of lower end parts of the detachable grille section.

50 14. A grill as per claim 11, in which the said socket comprises an upwardly U-sectioned member normally having its U-shanks respectively engaging forward and rearward portions of lower end parts of the detachable grille section, the 45 said U-sectioned member being fast with respect to the part of the bottom cross-member which extends between the blades of the first named two sets.

55 15. A grille as per claim 11, in which the stop means comprise a member fastened to the said second cross-member, against which member the blades of the detachable grille normally bear rearwardly.

60 16. A grille as per claim 11, in which the cross-bars of the detachable grille section normally

have their ends abutting respectively against the laterally innermost blades of the said two sets.

17. A grille as per claim 11, in which the latching means comprise a spring latch fast with respect to the upper portion of the detachable grille section, and a latch-engaging member fast with respect to the said second cross-member.

5 18. A grille as per claim 11, in which the latching means comprise a spring latch fast with respect to the upper portion of the detachable grille 10 section; and a latch-engaging member fast with respect to the said second cross-member; the latch-engaging member presenting its latch-engaging portion at lower elevation than the said cross-member.

15 19. A grille as per claim 11, in which the latching means comprise a latch-engaging member fastened to the second cross-member, the latch-engaging member including both an approximately upright web forming the said stop means and a web extending rearwardly from the said flange; and in which the latching means also include a spring fastened to the detachable grille section, the spring bearing normally both upwardly and forwardly against the rear edge portion of the 20 said web.

20 20. A grille as per claim 11, in which the latching means comprise a latch-engaging member fastened to the second cross-member, the latch-engaging member including both an approximately upright web forming the said stop means and a web extending rearwardly from the said flange; and in which the latching means also include a spring fastened to the detachable grille 25 section, the spring having a portion thereof normally engaging the rear edge of the said web, the said web sloping downward rearwardly.

30 21. A grille as per claim 11, in which the latching means comprise a latch-engaging member fastened to the second cross-member, the latch-engaging member including both an approximately upright web forming the said stop means and a web extending rearwardly from the said flange; and in which the latching means also include a spring fastened to the detachable grille 35 section, the spring having a portion thereof normally engaging the rear edge of the said web, the said web sloping downward rearwardly.

40 22. A grill as per claim 11, in which the latching means comprise a latch-engaging member

45 fastened to the said second cross-member, and a spring formed of flat metal and having a rearward portion normally bearing forwardly against the latch-engaging member; the forward portion of the spring being in straddling relation to a blade of the detachable section of the grille, and the spring having a portion thereof intermediate of its length fastened to a cross-bar of the 50 detachable section.

LEE B. GREEN.
